L. C. GIERYMSKI AND C. BOHDANOVICZ.

ROPE OR CABLE CONNECTOR AND GRIP.

APPLICATION FILED MAR 1, 1922.

1,427,284.

Patented Aug. 29, 1922.

UNITED STATES PATENT OFFICE.

LEOPOLD C. GIERYMSKI AND CASIMIR BOHDANOVICZ, OF NEW BRITAIN, CONNECTICUT.

ROPE OR CABLE CONNECTOR AND GRIP.

1,427,284.

Specification of Letters Patent. Patented Aug. 29, 1922.

Application filed March 1, 1922. Serial No. 540,263.

To all whom it may concern:

Be it known that we, LEOPOLD C. GIERYMSKI and CASIMIR BOHDANOVICZ, citizens of the United States, residing at New Britain, 5 in the county of Hartford and State of Connecticut, have invented certain new and useful Improvements in Rope or Cable Connectors and Grips, of which the following is a specification, reference being had to 10 the accompanying drawings.

It is the purpose of the present invention to provide a device of this kind particularly adapted for use in connection with clothes-lines, for connecting and gripping 15 the opposite ends of a clothes-line, which passes over oppositely disposed pulleys. However, it is obvious that this device may be applied to cables or ropes used for other purposes.

20 Another purpose is the provision of a device of this character, wherein a U-shaped plate is employed, including camming means in the opposite walls of the plate, with which a clamp cooperates, for clinching 25 or gripping one end of the cable or rope, which constitutes the clothes-line.

Still another purpose is the provision of a pulley mounted in the opposite walls of the plate, and so disposed relatively to the 30 ends of slots in which the gripping or clinching device is mounted, so as to prevent the removal of said clinching or gripping device, after once arranged in position in the slots. The pulley is engaged by one end of the cable 35 or rope or clothes-line, so that by pulling on the end of the rope, the gripping or clinching device may be moved through the action of the rope or cable moving in a direction and over the pulley.

40 By the arrangement and construction of a gripping and coupling device as herein illustrated and described, it is very easy to connect, couple or grip the opposite ends of a clothes-line, or the opposite ends of a 45 cable or rope used for other purposes.

A further purpose is the provision of an improved clinching or gripping device movably mounted in the side walls of a plate and provided with a centrally arranged enlarged or bulged portion, to insure a firm clinch or grip on the rope or cable, when 50 engaged between the device and one edge wall of the plate.

While the design and construction at 55 present illustrated and set forth are deemed preferable, it is obvious that as a result of

a reduction of the invention to a more practical form for commercial purposes, the invention may be susceptible of changes, and the right to these changes is claimed, provided they are comprehended within the scope of what is claimed. 60

The invention comprises further features and combination of parts, as will be herein-after set forth, shown in the drawings and 65 claimed.

In the drawings:—

Figure 1 is a view in side elevation of a suitable clothes-line, showing the improved gripping or connecting device as applied; 70

Figure 2 is a longitudinal sectional view;

Figure 3 is a cross sectional view on line 3—3 of Figure 1;

Figure 4 is a cross sectional view on line 4—4 of Figure 1; and 75

Figure 5 is a view in side elevation of a coupling and gripping device, including a modified structure of slots in the opposite side walls of a plate, for holding and operating the gripping or clinching means. 80

Referring to the drawings, 1 designates a clothes-line, though it is obvious that the coupling and gripping device may be applied to other ropes or cables used for other purposes. This coupling or gripping device 85 comprises a plate 2, which is U-shaped, though it may be otherwise constructed and shaped, and the opposite side walls of the plate are provided with registering slots 3 and 4. In fact there are two slots 3 and 90

two slots 4, and engaging the registering slots 3 is a headed pin 5, the heads acting to prevent endwise movement of the pin. The end portions 6 of the slots 3 are enlarged, as shown at 7, in order to permit the pin 5 to 95 be inserted, and after being inserted, the pin 5 may be removed toward and engage the opposite ends of the slots 3, in which case the heads of the pin prevent the pin from moving axially. One end of the cable, 100 or clothes-line is engaged about the pin 5, between the opposite walls of the plate 2, and the terminal of the rope or cable is wrapped or bound to the body of the cable or rope by means of heavy cord 8, to insure 105 a secure connection of the cable to the pin 5.

The slots 4 are arranged on an inclination, in fact at an angle to the wall 9 of the plate, and engaging the slots 4 is a gripping or clinching pin or roller 10. The central 110 portion of the pin or roller 10 is enlarged, as shown at 11, and its heads 12 (which are of

the same diameter as the enlarged central portion 11), act to prevent axial or endwise movement of the roller 10. The purpose of constructing the slots 4 on an inclination 5 or at an angle to the wall 9 of the plate 2, is to enable the roller or clinching device 10 to cooperate with the wall 9, for the purpose of clamping the rope or cable 1, that is to say when the roller or gripping device 10 is 10 moved in a direction toward the wall 9. The end portions 13 of the slots 4 are enlarged as shown at 14, of a diameter sufficiently to permit either one of the heads 12, and the enlarged portion 11 of the roller or pin 10 15 to pass therethrough, for the purpose of arranging the pin or roller in the slots. After the pin or roller has been disposed in the slots 4, and moved in a direction toward the smaller ends of the slots, the heads 12 act 20 to prevent axial movement of the roller.

This roller or pin 10, as well as the pin 5 are placed in engagement with the slots 3 and 4 before journaling a pin 15 in bearings of the side walls of the plate 2. At the 25 same time the pin 15 is mounted in the bearings of the side walls of the plate 2, a roller or pulley 16 is journaled upon the pin, whereby one end of the rope or cable 1 may pass over the pulley or roller 16. It will be 30 noted that the roller or pin 16 is of a diameter, so that its flanges overlie the marginal edges of the enlarged portions 7 and 14 of the slots 3 and 4. Obviously this overlapping construction of the pulley or roller 16 35 relatively to the enlarged portions 7 and 14 of the slots 3 and 4 prevents the pins 5 and 10 from being removed from the slots, after they have once been mounted in position. In fact the only way to remove the pin 5, or 40 the roller or pin 10, is to file or otherwise cut off one of the heads of the pin 5, permitting the pulley or roller 16 to be removed, as well as allowing a detachment of the pulley or wheel 16.

45 In Figure 5, the corresponding edges of the slots 4 are provided with teeth 17, which are engaged by the teeth 18 of the headed pin 19, enabling the roller or pin 19 to rotate in the slots 4, without slipping, and thereby securely clamp the cable or rope 50 against the wall 9 of the plate 2.

While it is obvious that by pulling upon the extremity 20 of the cable or rope, in order to tighten the cable, it is also possible 55 to pull the extremity 20, to cause the roller or pin 10 to disengage from the cable or rope, that is to say if the rope or cable is sufficiently slack to permit it to give, whereby movement may be imparted to the pin 60 10 in the direction of the arrow α . In fact when the rope or cable is pulled, it is possible to start the pin or roller 10 toward the enlarged ends of the slots 4, then the rope or cable 1 is capable of movement, or capable 65 of being tightened or loosened. The

present form coupling and gripping device may be used in connection with various ropes, cables or the like, whether they are used as clothes-lines or whether they are used for other purposes. 70

The invention having been set forth, what is claimed is:—

1. A coupling and gripping device comprising a U-formed body, to one end of which one end of a rope or cable is permanently attached, said body at its other end having cammed slots inclined relatively to one wall of the body, a clinching or gripping member movably mounted in said slots, and adapted to clamp the other end of said rope 75 between it and said wall of the body, a pulley journaled in the side walls of the body and over which one end of the rope engages, when pulling the rope to cause the gripping members to clamp against the rope. 80

2. A coupling and gripping device comprising a U-formed body, to one end of which one end of a rope or cable is permanently attached, said body at its other end having cammed slots inclined relatively to 90 one wall of the body, a clinching or gripping member movably mounted in said slots, and adapted to clamp the other end of said rope between it and said wall of the body, a pulley journaled in the side walls of the 95 body and over which one end of the rope engages, when pulling the rope to cause the gripping members to clamp against the rope, corresponding ends of said slots being enlarged to permit the clinching or gripping member to be inserted transversely of and within the slots, the arrangement and construction of said pulley relatively to the enlarged ends of the slots being such as to overlap said enlarged ends to prevent the removal of the clinching or gripping device 100 after it has been arranged in the slots. 105

3. In a coupling and gripping device, a U-formed body having means at one end thereof to effect a permanent attachment of one 110 end of a rope thereto, the other end of the body having cammed slots inclined relatively to a transverse wall of the body, a headed roller pin mounted in the slots and adapted to be engaged by the other end of the rope, the tension upon which causes the roller to move toward the ends of the slots nearest the transverse wall, to cause the roller to grip the rope between it and the transverse wall, corresponding ends of the 115 slots being engaged to permit the headed roller pin to be arranged in the slots, and rope engaging means journaled between the sides of the U-formed body and overlapping the enlarged portions of the slots to prevent 120 the removal of the headed roller pin after the same has once been inserted. 125

4. In a coupling and gripping device, a U-formed body having means at one end thereof to effect a permanent attachment of one 130

end of a rope thereto, the other end of the body having cammed slots inclined relatively to a transverse wall of the body, a headed roller pin mounted in the slots and adapted 5 to be engaged by the other end of the rope, the tension upon which causes the roller to move toward the ends of the slots nearest the transverse wall, to cause the roller to grip the rope between it and the transverse 10 wall, corresponding ends of the slots being engaged to permit the headed roller pin to be arranged in the slots, and rope engaging means journaled between the sides of the U-formed body and overlapping the enlarged 15 portions of the slots to prevent the removal of the headed roller pin after the same has once been inserted, said roller pin having gear teeth engagement connections with certain of the edges of said slots, to insure a 20 positive rolling action of the roller pin, to cause it to clamp against the rope.

5. In a coupling and gripping device, a U-formed body having means at one end thereof to effect a permanent attachment of one 25 end of a rope thereto, the other end of the body having cammed slots inclined relatively to a transverse wall of the body, a headed

roller pin mounted in the slots and adapted to be engaged by the other end of the rope, the tension upon which causes the roller to move toward the ends of the slots nearest the transverse wall, to cause the roller to grip the rope between it and the transverse wall, corresponding ends of the slots being engaged to permit the headed roller pin to be arranged in the slots, and rope engaging means journaled between the sides of the U-formed body and overlapping the enlarged portions of the slots to prevent the removal of the headed roller pin after the same has once been inserted, said roller pin having gear teeth engagement connections with certain of the edges of said slots, to insure a positive rolling action of the roller pin, to cause it to clamp against the rope, 45 the central portion of the roller pin having an enlargement of curved form, to insure a binding engagement of the rope, when the roller pin is moved in a direction toward the transverse wall.

In testimony whereof we hereunto affix our signatures.

LEOPOLD C. GIERYMSKI.
CASIMIR BOHDANOVICZ.
